Inventor

Samuel Mathez

By his Attorney
Dean Fairbank, Obrecht & Hinck

UNITED STATES PATENT OFFICE.

SAMUEL MATHEZ, OF BROOKLYN, NEW YORK.

DIAL FOR WATCHES OR CLOCKS.

Application filed March 1, 1926. Serial No. 91,318.

This invention relates to watches or clocks of the type in which means are provided for indicating the seconds as well as the minutes and hours.

5 One of the main objects of my invention is to improve the appearance of the dial by so designing and mounting the second indicating mechanism that all of the hour numerals may appear on the dial. In the 10 ordinary watch having a second hand, the hour numeral "6" is omitted, as the dial of the second hand comes closely adjacent to the lower edge of the main dial.

15 A further object of my invention is to provide a second indicating member which although visible through a movement of only 180°, serves to indicate the seconds throughout the full 360° of rotation.

20 In the accompanying drawing to which reference is to be had, I have illustrated two forms which my invention may assume, although it will be evident that other forms may be designed within the scope of my invention. In the drawing:

25 Fig. 1 is a face view of a watch constructed in accordance with my invention.

Fig. 2 is a face view of the rotatable second indicating member.

30 Fig. 3 is a section on the line 4—4 of Fig. 1.

I have illustrated my invention as applied to a watch having a main dial A over which the hour and minute hands B and C move in the ordinary manner, and by any ordinary form of clock movement.

35 The dial, instead of having a separate second dial therein, has a slot D which is curved through 180° and has marked along one side thereof the numerals from zero 40 to thirty indicating the first thirty seconds of a minute, and the numerals thirty to sixty along the opposite side of the slot, indicating the second thirty seconds of the minute. Mounted on the usual pindle E I

45 provide a member which has an indicating portion movable along the slot. This member is mounted beneath the main dial A, and has only a portion thereof visible through the slot.

50 In the form shown, this member is in the form of a disk F which has two indicating portions spaced 180° apart, and moved along the slot in succession. These indicating portions are a pointer G directed toward

55 the outer edge of the slot, and a pointer H directed toward the inner end of the slot.

For instance, the disk F may have a black ring J painted or otherwise formed thereon, and the pointer G may be in the form of a black triangle extending outwardly from this ring, while the pointer H may be a notch in the outer side of the black ring constituting a white inwardly directed triangle. During one half of the revolution of the disk F, the pointer G will be visible 60 through the slot and will be directed toward and move along the outer series of numerals zero to thirty, while during the next half revolution the pointer H will be visible 65 through the slot and will be directed toward the inner series of numerals thirty to sixty. As the pointers G and H are 180° apart, each pointer will disappear at thirty at the instant that the other one appears at the other numeral 70 thirty. The disk F has two concentric zones, 75 one black and the other white, and each having a pointer portion directed into the other zone. Although this is a desirable construction, it is not essential to my invention.

Having thus described my invention, what I claim as new and desire to secure by Letters Patent is:—

1. A dial for watches or clocks having an arcuate slot extending through substantially 80 180°, the center portion of the slot being spaced from and below the center of the dial and the ends of the slot curving downwardly in opposite directions toward the periphery, two concentric scales, one extending along the outer edge of said slot 85 and the other along the inner edge of the slot, one of said scales being calibrated from 0 to 30 and the other from 30 to 60, and a disc mounted beneath said dial and adapted for rotation about the center of curvature of 90 said slot, said disc having two pointer portions indicated thereon at diametrically opposite points adjacent to the periphery, one of said pointer portions being directed outwardly for registry with one of said scales 95 and the other directed inwardly for registry with the other of said scales.

2. A dial for watches or clocks having an arcuate slot extending through substantially 100 180°, the center portion of the slot being adjacent to, but spaced from the center of the dial, and the end of said slot curving toward the periphery of the dial, two scales, one calibrated from 0 to 30 and disposed along one edge of said slot and the other 105 calibrated from 30 to 60 and disposed along the other edge of said slot, a rotatable disc

beneath said dial and having its center coincident with the center of curvature of said slot, said disc having a pair of concentric bands of different colors adjacent to the periphery thereof and beneath said slot, each of said bands having a notch therein of a color corresponding to that of the other band and at diametrically opposite points,

whereby one of said notches moves along one of said scales and the other along the other of said scales during the rotation of said disc.

Signed at New York, in the county of New York and State of New York this 26th day of February, A. D. 1926.

SAMUEL MATHEZ.
